H. M. WILLIAMS,
SIGNALING DEVICE,
APPLICATION FILED JUNE 19, 1919.

1,376,127.

Patented Apr. 26, 1921.

Inventor
Harry M. Williams.

Attorney

UNITED STATES PATENT OFFICE.

HARRY M. WILLIAMS, OF LITTLE ROCK, ARKANSAS, ASSIGNOR OF ONE-HALF TO
JOHN E. COATES, OF LITTLE ROCK, ARKANSAS.

SIGNALING DEVICE.

1,376,127.

Specification of Letters Patent. Patented Apr. 26, 1921.

Application filed June 19, 1919. Serial No. 305,291.

To all whom it may concern:

Be it known that I, HARRY M. WILLIAMS, a citizen of the United States, residing at Little Rock, county of Pulaski, and State of Arkansas, have invented certain new and useful Improvements in Signaling Devices, of which the following is a specification.

My invention relates to signaling devices, and particularly to a holder for signal flags. The object of my invention is to provide in a signaling device means for supporting a signal flag while displaying and which will protect the same from becoming soiled or injured by the weather when furled. While my invention may be used for various signaling devices and purposes, it is particularly adapted for use in conjunction with railway rolling stock for displaying and protecting the classification flags such as displayed on the locomotive and at the rear end of the train. To this end, a further object of my invention is to provide a signaling device of the class mentioned equipped with means for supporting the same in position on the train.

A further object of my invention is to provide a device of the character mentioned which shall be of low cost to manufacture and which will not readily get out of order. A further object of my invention is to provide a device of the character mentioned adapted to hold a plurality of signaling flags and equipped with means to prevent the unrolling of the flag or flags within the container. Other objects will appear herein-after.

With these objects in view, my invention consists generally of a tubular body provided with a longitudinal slot extending substantially the full length thereof, a closure for the upper end of said container, a flag staff on the inner end of said closure, and means for supporting the device in position. My invention further consists in providing a plurality of tubular containers, one of which is provided with the longitudinal slot above mentioned in combination with interchangeable closures for the upper ends of said containers, and flag staffs on said closures, whereby each of said flag staffs may be equipped with a flag of a different color and the flag of the desired color arranged within the container having the longitudinal slot to permit the flag being extended through said slot for display. My

invention further consists in various details of construction and arrangements of parts all as will be fully described hereinafter and particularly pointed out in the claims.

My invention will be more readily understood by reference to the accompanying drawings forming a part of this specification and in which,

Figure 1 is a front elevation of a signaling device embodying my invention in its preferred form.

Fig. 2 is a side elevation thereof.

Fig. 3 is a vertical section through the device showing a slightly modified form of supporting means.

Fig. 4 is a top plan view.

Fig. 5 is a transverse section on the line 5—5 of Fig. 1.

Fig. 6 is a plan view with the closures and staffs removed.

Fig. 7 is a side elevation of the upper end of the slotted container, illustrated upon an enlarged scale.

Fig. 8 is a detail sectional view of the upper end of one of the containers, upon an enlarged scale, and illustrating the closure in position thereon, and

Fig. 9 is a top plan view of a modified form of the device with the closures removed.

Referring now to Figs. 1 to 6 of the drawings, 1 and 2 indicate a pair of tubular containers the lower ends of which are secured in any suitable manner, as by soldering, to a base 3. The upper ends of the containers are secured together by a band 4. The containers 1 and 2 may be formed of sheet metal, of old pieces of pipe, or any suitable tubular material, so that the actual cost of the device may be reduced to a minimum. The container 1 is formed with a longitudinal slot 5 extending substantially throughout the length thereof and this is preferably positioned on the side of the container opposite the container 2. Each of the containers is provided with a closure 6. This comprises a plug portion 7 adapted to fit within the upper end of the container, an annular flange 8 adapted to rest upon the upper edge of the container and extend slightly beyond the periphery thereof, and a head 9 constituting a handle to facilitate manipulating the device. The flanges 8, by projecting beyond the periphery of the containers, effectually exclude the weather

from entering the upper ends thereof and limit the inward movement of the closure. Extending inwardly from the plug 7 is a flag staff 10 to which is secured the signal flag 11, each flag being of a different color.

In using the device for train classification flags, two containers are sufficient, one for the white flag and one for the green, such flags being the ones usually employed by railroads for this purpose. However, if a greater variety of flags is desired, the number of containers may be increased without departing from my invention, and in Fig. 9 I have illustrated three such containers, it being obvious that the number may be increased within reason to any number desired or found necessary for the particular purpose for which the device is to be employed. Suitable means are provided for supporting the device in position. This is preferably a depending pin 12 on the base plate 3, as shown in Figs. 1 and 2. However, the base plate 3 and the supporting device may be formed of a single piece of strap iron bent to form the base portion 3 and the depending supporting portion 13, as shown in Fig. 3.

In using the device, when no flags are to be displayed, the flags are furled upon their respective staffs and inserted within the several containers. When it is desired to display a flag, the flag of the suitable color is selected and placed within the container 1, projecting through the slot 3 as indicated in Fig. 5. To facilitate inserting the unfurled flag within the container 1, the upper end of the slot 5 is flared, as indicated at 14 in Fig. 7, and the adjacent ends of the band 4 are bent backwardly forming rounded beads 15, thereby forming a comparatively large mouth at the upper end of the slot. It is obvious that with this construc-

tion the flag may be readily and quickly inserted without injury to the same.

Preferably, I provide means to prevent rotation of the flag staffs within the containers to avoid unfurling or unwrapping of the flags therein. To this end the adjacent sides of the flanges 8 of the several closures are flattened, as at 16, (see Fig. 4) to fit against each other and thereby prevent said rotation.

I claim:—

1. A signaling device comprising a plurality of tubular containers, one of said containers being provided with a longitudinally-disposed slot, interchangeable closures for the ends of said containers, flag staffs fixed to said closures, and signal flags on said staffs, substantially as described. 55

2. A device as set forth in claim 1, in combination with a base secured to the lower ends of said containers, and a band connecting the upper ends of said containers, substantially as described. 60

3. A device as set forth in claim 1, in which the upper end of said slot is outwardly flared and the ends of said band being bent backwardly forming beads at each side of the end of said slot, substantially as described. 65

4. A device as set forth in claim 1 further characterized by flattened faces on the adjacent sides of said closures coöperating to prevent rotation thereof, substantially as described. 70

In testimony whereof I have signed my name to this specification in the presence of two subscribing witnesses.

HARRY M. WILLIAMS.
